US0D1112812S

(12) **United States Design Patent** (10) Patent No.: **US D1,112,812 S**
(45) Date of Patent: ** Feb. 10, 2026

(54) **TISSUE PROCESSING CARTRIDGE**

(71) Applicant: **AVITA Medical Americas, LLC**,
Valencia, CA (US)

(72) Inventors: **Niraj Kumar Doshi**, Valencia, CA
(US); **Paul Faucher**, San Diego, CA
(US); **Matthew Krywcu**, Laguna
Niguel, CA (US); **David Melby**,
Valencia, CA (US); **Carl Swindle**, San
Clemente, CA (US); **David Allen**
Fencil, Valencia, CA (US)

(73) Assignee: **Avita Medical Americas, LLC**,
Valencia, CA (US)

(**) Term: **15 Years**

(21) Appl. No.: **29/922,596**

(22) Filed: **Dec. 22, 2023**

(51) LOC (15) Cl. **24-02**

(52) U.S. Cl.

USPC **D24/224**

(58) **Field of Classification Search**

USPC D24/103, 123, 216, 224, 225, 227, 231;
D10/81; D14/679
CPC . A61B 10/00; A61B 17/32; B01L 3/00; B01L
11/00

See application file for complete search history.

CLAIM

The ornamental design for a tissue processing cartridge, as shown and described.

DESCRIPTION

FIG. 1 is a top, front, and right side perspective view of one embodiment of a tissue processing cartridge.

FIG. 2 is a front view of the tissue processing cartridge of FIG. 1.

FIG. 3 is a back view of the tissue processing cartridge of FIG. 1.

FIG. 4 is a left side view of the tissue processing cartridge of FIG. 1.

FIG. 5 is a right side view of the tissue processing cartridge of FIG. 1.

FIG. 6 is a top plan view of the tissue processing cartridge of FIG. 1.

FIG. 7 is a bottom plan view of the tissue processing cartridge of FIG. 1.

FIG. 8 is a top, front, and right side perspective view of another embodiment of a tissue processing cartridge.

FIG. 9 is a front view of the tissue processing cartridge of FIG. 8.

FIG. 10 is a back view of the tissue processing cartridge of FIG. 8.

FIG. 11 is a left side view of the tissue processing cartridge of FIG. 8.

FIG. 12 is a right side view of the tissue processing cartridge of FIG. 8.

FIG. 13 is a top plan view of the tissue processing cartridge of FIG. 8; and,

FIG. 14 is a bottom plan view of the tissue processing cartridge of FIG. 8.

The broken lines in the drawings depict portions of the tissue processing cartridge that form no part of the claimed design.
